NOISE SUPPRESSION CIRCUIT

Michael J. Di Toro, Brooklyn, N. Y., assignor to
Federal Telecommunication Laboratories, Inc.,
New York, N. Y., a corporation of Delaware

Application May 1, 1948, Serial No. 24,487

17 Claims. (Cl. 178—44)

1

The present invention relates to devices for the suppression of noises accompanying a signaling wave, for example a speech wave.

In known devices of this general character, the signal-to-noise ratio is usually improved by using a normally blocked transmission path for the speech wave which path becomes unblocked only when the input amplitude exceeds a predetermined level, so that only the spoken syllables but not the inter-syllable noises will be transmitted. Such a system, however, does not discriminate against inter-syllable disturbances of high level, such as sharp impulses, nor against low-amplitude disturbances coinciding with and superimposed upon the signals desired to be passed.

The principal object of the present invention is, therefore, to provide a noise suppression circuit which will be effective at all times to discriminate against all frequencies other than those characteristic of the particular speech or other signaling wave to be transmitted, whereby a large portion of the noises accompanying such wave will be substantially attenuated whether occurring during inter-syllable intervals or superimposed upon the speech signals.

In accordance with the present invention, there is thus provided in a system of the character described a wave filter having a plurality of resonance peaks at a fundamental frequency and harmonics thereof, said filter being preferably controlled by a current varying with the pitch of the wave (if a speech wave) so as to vary the fundamental frequency in accordance with the said pitch.

The wave filter referred to may be an electrical or mechanical resonator preferably terminated at both ends in a very high impedance. A suitable electrical resonator comprises an open-circuited artificial line whose fundamental resonance frequency may be varied, for example, by a system of pitch responsive relays arranged to cut in or out one or more sections of the line as required. A suitable mechanical resonator comprises an elongated vibratory member under tension, said member being electromagnetically excitable to oscillate at a fundamental frequency which is variable by adjusting the tension under which it is held.

The above-mentioned and other features and objects of this invention and the manner of attaining them will become more apparent and the invention itself will be better understood by reference to the following description of certain embodiments of the invention, taken in conjunction with the accompanying drawing in which:

Fig. 1 is a graph showing the frequency spectrum of a speech wave;

Fig. 2 is a graph illustrating the transmission characteristics of a wave filter of the character referred to;

2

Fig. 3 is a circuit arrangement showing an electric resonator represented by an artificial line;

Fig. 4 is a partial modification of the circuit arrangement of Fig. 3;

Fig. 5 is a circuit arrangement showing a mechanical resonator represented by an electrically conductive ribbon under tension;

Fig. 6 is a graph used to explain the operation of the arrangement of Fig. 5; and

Fig. 7 is a further partial modification of the circuit arrangement of Fig. 3.

Referring to the drawing, there is shown in Fig. 1 the frequency spectrum of a speech wave composed of a plurality of narrow frequency bands 2 of varying amplitudes A, the peaks of these bands forming an envelope 3. The frequency bands 2 occur at a fundamental frequency f_0 determining the pitch of the voice, and at a plurality of low harmonics of said fundamental, indicated for example at $2f_0$, $5f_0$ and $10f_0$. The amplitudes A of the respective frequency bands 2 and, therefore, the form of the envelope 3 varies constantly in accordance with the sounds formulated by the speaker; at the same time, the pitch of the voice and, with it, the location of f_0 , $2f_0$ etc. in the frequency band generally also varies, but at a relatively slow rate.

Let us now consider the transmission characteristics of a line of electrical length l which is open-circuited at the far end (or terminated in a very high impedance). The input impedance of such a transmission line becomes a maximum for electrical lengths equal to multiples of half the wave length of the incoming wave, thus $l = \lambda/2$, λ , $3\lambda/2$, 2λ etc. Since the wave length varies inversely with frequency, $\lambda = c/f$ (c being a constant), the input impedance will be a maximum for frequencies $f = c/\lambda$ wherein $\lambda = 2l$, l , $2l/3$, $l/2$ etc. Substituting, we find the resonance frequencies of the line equal to $c/2l$, $2c/2l$, $3c/2l$ etc. or, for $f_0 = c/2l$, $f = f_0$, $2f_0$, $3f_0$ etc. This is illustrated in Fig. 2 wherein curves 4 (solid lines) represent the input frequency Z_i of a transmission line of given electrical length at different input frequencies f .

Referring now to Fig. 3, there is shown an audio frequency amplifier 5 having input terminals 6, 7 and output terminals 8, 9, the latter being connected across a load resistor 10. The internal impedance of amplifier 5 should substantially exceed the resistance 10, thus constituting the amplifier a constant-current source. Resistor 10 is shunted by an artificial line 11 comprising a plurality of sections 11a, 11b, 11c, 11d, 11e, 11f and 11g. The line 11 is open-circuited at its far-end terminals 12, 13 and is normally broken at sections 11b, 11d and 11f, the breaks in the line being bridgeable by the armatures 14, 15 and 16 of respective relays 17, 18 and 19.

Returning to Fig. 2, it will be seen that the shunting of load resistor 10 by the input impedance Z_i of transmission line 11 will give rise to an output voltage versus frequency characteristic 20 (dotted lines), E_0 being the voltage developed across resistor 10 the magnitude of which is assumed to be large relative to the ohmic component of the characteristic impedance of line 11. For an ideal line having zero attenuation (such as assumed in the graph 4 of Fig. 2) the value of E_0 at frequencies f_0 , $2f_0$, $3f_0$ etc. will rise to a peak 21 determined solely by the magnitude of load resistor 10, this value being zero at odd multiples of frequency $f_0/2$ when the input impedance Z_i becomes negligible. In actual practice the shunting effect of line 11 will be more marked at the higher frequencies and the amplitudes of peaks 21 will decline as illustrated.

It will thus be seen from graph 20 in Fig. 2 that the output voltages developed across the load 10, 11 will be of appreciable magnitudes only in the neighborhood of resonance frequencies f_0 , $2f_0$, $3f_0$, etc. but will be more or less attenuated at all other frequencies. This is precisely the transmission characteristic required for the reproduction of the frequency spectrum of speech wave 1 (Fig. 1), provided the value of f_0 is the same in both instances. Since the fundamental of the speech wave varies, the electrical length of the line 11 and, thereby, the resonance frequency f_0 thereof should also vary. This can be accomplished by means of the relays 17, 18 and 19 which should be biased so as to be responsive to currents of successively greater magnitude. It will be seen that relays 17, 18 and 19 in Fig. 3 are connected in series with one another and with the output of a device 22 which is a source of control current varying in magnitude with the pitch of the speech wave applied to amplifier 5. The device 22 may be an audio frequency discriminator whose output current increases as the pitch of the incoming wave is lowered, and vice versa.

If, now, a wave of low pitch is applied to the input of amplifier 5 and discriminator 22, a current will flow through the three relay windings connected in series which will be large enough to overcome the bias of all three relays 17, 18 and 19, attracting armatures 14, 15 and 16 whereby the line 11 will be extended to its full length; this will cause the fundamental resonance frequency of the line to drop to the desired low value. As the pitch of the speech wave rises, relays 19, 18 and 17 will become successively de-energized, thereby progressively shortening the line 11 and raising its resonance frequency to values substantially equal to the new fundamental of the incoming wave. It will be understood that the drawing shows three control relays only by way of example, the number of relays required and the length of line controlled by each being of course determined by the circumstances.

Fig. 4 shows a modification of that part of the circuit of Fig. 3 which is to the right of line X-X. Here the discriminator 22 is terminated in a voltage divider 23 having taps 24, 25 and 26 connected to the grids of respective thyatron 27, 28 and 29 energized by a source of alternating current 30. The cathodes of the thyatron 27, 28 and 29 are biased by batteries 31, 32 and 33, respectively. Relays 17, 18 and 19, shunted by respective condensers 34, 35 and 36, are connected in the load circuits of thyatrons 27, 28 and 29, respectively.

As the current through voltage divider 23 increases, the tap 26 will first be sufficiently positive to overcome the bias of battery 31 and fire tube 27, thereby energizing the associated relay 17. For lower pitch, again, the magnitude of the control current will rise, thus successively energizing relays 17, 18 and 19 in the order named, and again resulting in a progressive lowering of the resonance frequency f_0 . It will be appreciated that the provision of thyatrons 27, 28 and 29 permits a substantially instantaneous energization and de-energization of relays 17, 18 and 19, respectively, whereby the fidelity of the reproduction will be enhanced.

While in the foregoing there have been disclosed certain arrangements for varying the transmission characteristic of a wave filter by discrete stages, there will be now described a further embodiment of the invention wherein the location of the pass bands is continuously variable. Referring to Fig. 5, which also serves to illustrate the use of a mechanical in lieu of an electrical resonator, there is shown a permanent magnet 37 and a metal ribbon 38 suspended for free vibratory motion transverse to the gap 39 of the magnet. Ribbon 38 is electrically connected across the input terminals 6, 7 by way of a coupling condenser 40 inserted between terminal 6 and the left-hand end 41 of the ribbon, the right-hand end 42 of the ribbon being grounded as is the other terminal 7.

The flow of audio frequency currents through the condenser 40 and ribbon 38 will set the latter in oscillatory motion transverse to the gap 39 of magnet 37, as indicated by the arrow 43. To provide a high-impedance termination with respect to such oscillations, the end 41 is rigidly engaged by an anchorage 44 and the end 42 is held against displacement in the direction of arrow 43 by flexible anchorages 45, 46. A contracting spring 47 applies tension to the end 42 through the intermediary of a rod 48, both the spring 47 and the rod 48 being secured to the upper extremity of the vertical arm 49 of a bell crank lever 50. Lever 50 is pivoted at 51 and carries an armature 52 at the extremity of its horizontal arm 53.

Audio frequency discriminator 22, connected as in Fig. 3 across the input terminals 6 and 7, delivers a control current which energizes an electromagnet 54 attracting the armature 52 of lever 50. Thus the pull of magnet 54 opposes the force exerted by the spring 47 and tends to relax the tension in ribbon 38. A conductor plate 55 is positioned close to the ribbon 38 adjacent the end 42 thereof, this plate being connected in series with a battery 56 and an output resistor 57 grounded at 58. Output terminals 8, 9 are connected across the resistor 57 by way of a coupling condenser 59. It will be seen that the ribbon 38 and the plate 55 form a condenser connecting the positive terminal of battery 56 to ground at 60 and that, as the ribbon 38 vibrates, the capacitance of this condenser will vary, thereby setting up electrical oscillations across output resistor 57 and terminals 8, 9.

The diagram of Fig. 6 shows, schematically, the ribbon 38 swinging in several modes of oscillation at a fundamental frequency having the wave form 61 and second, third and fourth harmonics indicated at 62, 63 and 64, respectively. The appearance of wave forms 61, 62, 63 and 64 are the result of excitation of the ribbon by an input wave containing the frequencies f_0 , $2f_0$, $3f_0$ and $4f_0$, f_0 being the frequency corresponding to the

ribbon's first mode of oscillation as indicated at 61. Frequencies which are not integral multiples of f_0 will not be able to excite the ribbon 38 to any appreciable degree, in view of the high-impedance terminations provided at the ends 41 and 42 thereof. At the same time it will be desirable to locate the exciting means 37 and the energy abstracting means 55 rather closely to the ends of the ribbon, in order to avoid the nodal points of important frequencies. Hence it will be seen that the disposition of magnet 37 and condenser plate 55 within the first and the last one-eighth of length (as indicated by lines Y—Y and Z—Z, respectively) will result in the transmission of appreciable amplitudes of the fourth harmonic and higher, whereas the arrangement of either of said elements near the center of the ribbon would seriously reduce the amplitudes of all even harmonics.

Since an increase in the output current of discriminator 22 will act to reduce the tension in ribbon 38, such an increase will lower the fundamental frequency f_0 at which the ribbon goes into its first mode of oscillation, indicated at 61. Since any change in the magnitude of the control current will be essentially continuous, the drop or rise in the resonance frequency of ribbon 38 will also be gradual and may be made to correspond accurately to the variations in the pitch of the speech wave. It will of course also be possible to let the control current decrease with falling pitch, in which case the position of the bell crank lever 50 should be reversed so that the pull of a magnet or solenoid acting thereon will reinforce the tension of spring 47.

Although the provision of means for continuously varying the pass bands of a wave filter has been described with reference to a mechanical resonator, it is within the scope of the invention to provide means for continuously varying the transmission characteristics of an electrical resonator of the general type illustrated in Figs. 3 and 4 or, if desired, to arrange for the stepwise variation of the fundamental frequency of a vibrating body such as shown in Fig. 5. Continuously-variable electrical resonators may comprise, for example, an artificial line similar to line 11 but incorporating one or more reactance tubes of the type well known in conventional frequency modulators. This is illustrated in Fig. 7 which shows a further modification of that portion of the system of Fig. 3 which is located to the right of line X—X.

In Fig. 7, a pair of reactance tubes 65, 66 are connected across the transmission line in parallel with respective shunt condensers of the line. Each of these tubes is shown as a conventional triode, having its grid connected to an intermediate terminal of a voltage divider which consists of a resistor 67 and that portion of resistor 23 which lies between tap 24 and ground, resistor 23 being again connected across the output of audio frequency discriminator 22 (Fig. 3). The voltage divider referred to forms part of a differentiation circuit which further includes condenser 68 connecting resistor 67 to the plate of the tube. Hence the high frequency voltage variations appearing across the transmission line will be applied with a lead of substantially 90 degrees to the grid of tubes 65 and 66, these tubes thus acting as capacitances of a magnitude which will be variable in accordance with the low frequency bias derived from resistor 23.

Only two tubes are shown by way of example. The number of tubes actually used will of course

depend on the circumstances as will the electrical length of the line. An obvious modification includes the use of reactance tubes of the inductive type in the series arms of the line, either instead of or in combination with the capacitive reactance tubes connected in the shunt arms.

It will be appreciated that the arrangement of Fig. 7 permits not only a continuous but also a relatively rapid adjustment of the electrical length of the line in accordance with the principles previously set forth.

Finally, it should be noted that the frequency spectrum shown in Fig. 1 corresponds to that of voiced sounds (vowels and voiced consonants such as *b*, *m* or *s*) which are the only components of a speech wave requiring a transmission channel whose fundamental resonance frequency varies with pitch. The unvoiced sounds (such as *p*, *ch*, *sh*) may be transmitted over a channel having a harmonic pass band which is substantially fixed and independent of pitch. Referring to Fig. 3, there is shown at 69 a bypass for unvoiced sounds which may include a wave filter of the type disclosed hereinabove, e. g. comprising a transmission line 11 which, however, will be of fixed electrical length. While the provision of such a bypass will not generally result in an undue decrease in the signal-to-noise ratio, it will of course be possible to use a frequency sensitive network for blocking this bypass during the time when frequencies characteristic of certain sounds (e. g. vowels) are transmitted.

While it is believed that the invention will be particularly useful in connection with systems for the transmission and reception of speech waves, it will be found to be applicable to any kind of signaling system wherein a periodic signal is to be separated from accompanying noises. Such periodic signals occur, for example, in radar systems, direction finders, navigational guides and the like.

Accordingly, while the principles of the invention have been described in connection with certain specific embodiments, it is to be clearly understood that this description is made only by way of example and not as a limitation upon the scope of the present invention.

What is claimed is:

1. A device for suppressing noises accompanying a signaling wave, comprising a source of a signaling wave, filter means having a plurality of resonance peaks at a fundamental frequency and harmonics thereof to which said signaling wave is applied, a source of control current, means for applying the signaling wave to said source to control its output responsive to the frequency spectrum of said wave, and means including said source for varying the said fundamental frequency to follow the changes in a frequency in said frequency spectrum, which frequency is the same as, or harmonically related to, said fundamental frequency.

2. A device according to claim 1 wherein said filter means comprises a resonator terminated in a high impedance at both ends.

3. A device according to claim 2 wherein said resonator is an electrical transmission line.

4. A device according to claim 3 wherein said signaling wave is a speech wave, further comprising control means responsive to changes in the pitch of said speech wave for varying the electrical length of said transmission line so as to maintain the fundamental frequencies of said line and of said speech wave substantially equal to each other.

5. A device according to claim 1 wherein said filter means comprises a resonator terminated in a high impedance at both ends, said resonator being an elongated resilient element under tension.

6. A device according to claim 5 wherein said signaling wave is a speech wave, further comprising control means responsive to changes in the pitch of said speech wave for varying the tension of said element so as to maintain the fundamental frequencies of said element and of said speech wave substantially equal to each other.

7. A system for transmitting a speech wave comprising a load across which said speech wave is developed and a transmission line in shunt with said load, said transmission line being substantially open-circuited at the far end thereof and being of such an electrical length that its fundamental resonance frequency substantially coincides with the resonance frequency of said speech wave, said transmission line being an artificial line composed of a plurality of sections, further comprising control means responsive to changes in the pitch of said speech wave for varying the number of sections in said line so as to maintain the fundamental frequencies of said line and of said speech wave substantially equal to each other.

8. A system according to claim 7 wherein said control means comprise a source of current and a plurality of relays respectively arranged to respond to different magnitudes of said current to connect additional ones of said sections to said line.

9. A system according to claim 8 wherein said control means further comprise a plurality of thyratrons each having a load circuit including a respective one of said relays, voltage divider means connected across the output of said source, and means including said voltage divider means for selectively energizing said thyratrons in accordance with the magnitude of the current flowing through said voltage divider means.

10. A system for transmitting a speech wave comprising a resistor across which said speech wave is developed, an artificial line shunted across said resistor, the magnitude of said resistor being high relative to the ohmic component of the characteristic impedance of said line, said line being composed of a plurality of sections and being terminated in a relatively high impedance at the far end thereof, and means for open-circuiting said line at certain of said sections for varying the electrical length of the line in such a manner that the fundamental frequency of the line corresponds substantially to the fundamental frequency of the said speech wave, said means comprising a source of control current responsive to the pitch of said speech wave and a plurality of relays selectively responsive to the magnitude of said current.

11. A system according to claim 1 wherein said filter is an artificial line composed of reactive elements, said elements including at least one reactance tube, said means for varying the fundamental frequency comprising control means responsive to changes in the pitch of said speech wave for varying the bias of said reactance tube so as to maintain the fundamental frequencies of said line and of said speech wave substantially equal to each other.

12. A system for transmitting a speech wave comprising an elongated vibratory electrical conductor, magnetic means producing a flux across

said conductor, anchor means suspending said conductor for vibration transverse to said flux while opposing such vibration at both ends of said conductor, means for maintaining said conductor under tension, circuit means for setting up in said conductor electric currents corresponding to said speech wave, said conductor having a fundamental frequency of vibration substantially corresponding to the fundamental frequency of said speech wave, an output circuit including a conductive element positioned adjacent said conductor to constitute said conductor and said element a capacitor, whereby electrical oscillations corresponding to the vibrations of said conductor will be set up in said output circuit, and control means responsive to changes in the pitch of said speech wave for varying the tension of said conductor so as to maintain said fundamental frequency of vibration substantially equal to the fundamental frequency of said speech wave.

13. A system according to claim 12 wherein said control means comprise a source of current and electromagnetic means operable by said current to modify the action of said means for maintaining said conductor under tension.

14. A system according to claim 13 wherein said last-mentioned means comprises a contracting spring, said electromagnetic means being operable to oppose the action of said spring.

15. A system according to claim 12 wherein said magnetic means and said conductive element are positioned adjacent opposite ends of said elongated conductor, respectively.

16. In a system for transmitting a signaling wave, in combination, a plurality of parallel transmission channels each comprising a wave filter having a plurality of resonance peaks at a fundamental frequency and harmonics thereof, a source of control current responsive to the frequency spectrum of said wave, means including said source for varying the fundamental frequency of at least one of said filters to follow the changes in one of the frequencies of said frequency spectrum, said one of the frequencies being the same as, or harmonically related to, said fundamental frequency, and means for combining the outputs of said channels.

17. In a system for transmitting a signaling wave, in combination, a plurality of parallel transmission channels, a first wave filter in one of said channels adapted to pass frequencies corresponding to voiced sounds of said speech wave, a second wave filter in another of said channels adapted to pass frequencies corresponding to unvoiced sounds of said speech wave, a control network responsive to changes in the pitch of said speech wave, means including said control network for varying the location of the pass bands of said first wave filter to follow the changes in said pitch, and means for combining the outputs of said channels.
